SCAFFOLDING

John P. Biebel, Belleville, Ill.

Application May 23, 1935, Serial No. 23,067

6 Claims. (Cl. 304—18)

My invention relates to scaffolding, and, more particularly to a portable scaffold.

The invention has for an object to provide a device of the class mentioned, which is of simple and durable construction, dependable in use, and efficient in action, and, which can be manufactured and sold at a reasonable cost.

Another object of my invention is the provision of a run board and work board supporting structure, which is suspended from a single cable.

A further object of the invention is the provision of a vertically disposed sleeve carried by the upper end of the suspended structure for guiding a hoisting cable to prevent undue swinging of the suspended structure due to obtaining an evenly distributed weight at the lower end of the cable.

A further object of the invention is the provision of a standard or support, which is provided with a flexibly resilient member at its upper end adapted to be supported between the guttering and the cornice of a building with the lower end thereof resting on the ground, and also providing the support with an eye from which a single cable is suspended.

A further object of the invention resides in the provision of hoisting means for winding the cable upon a drum and unwinding it therefrom for raising and lowering the suspended structure which supports the run and work supporting boards.

For further comprehension of the invention, and of the objects and advantages thereof, reference will be had to the following description and accompanying drawing, and to the appended claims, in which the various novel features of the invention are more particularly set forth.

In the accompanying drawing forming a part 40 of this disclosure:—

Fig. 1 is a side elevation of a suspended scaffold embodying the features of my invention.

Fig. 2 is a side elevation of the suspended scaffold structure.

Fig. 3 is a front elevation of same.

Fig. 4 is a top plan view of same.

Fig. 5 is a detail in perspective of the upper end of the standard or support from which the cable suspends for supporting the suspended scaffold structure.

In Fig. 1 of the drawing, the reference character 1 designates the roof of a building, 2, the side wall thereof, 3, the cornice and 4, a gutter secured to and carried by the cornice in the usual manner.

The invention comprises a suitable standard or support 5, and a cornice and gutter engaging member 6 of flexible resilient or spring metal, which projects beyond the upper end of the support, and, which is secured to the support by means of a suitable fastening device designated 7, and eye bolt 8, and, from which eye bolt 8 a suitable hoisting cable 9 is detachably connected through the medium of a hook 10, so that the cable will be vertically suspended therefrom. 10 The support 5 is adapted to stand alongside of the building wall 3 in an inclined position with the spring metal member 6 insertable between the cornice 3 and the gutter 4. The standard, or support 5 may be made of any suitable material such as two-by-four or other dimensioned lumber, which is easy to handle and transport from one place to another, and it may be formed of a single piece of material, or of a plurality of pieces suitably joined by loop members 11 and 20 securing pins 12.

The lower end of the cable 9 is adapted to be wound upon a suitable drum 13 rotatably mounted by means of a shaft 14 between the members 15 of a suitable frame like structure designated generally as 16. The upper ends of the frame members 15 are suitably secured to a suitable vertically disposed sleeve 17 which serves as a guide for the cable 9 through which it passes adjacent and above the drum 13. 30

The means for rotating the drum 13 includes a worm gear 18 secured to one end of the shaft 14 and a worm 19 which engages the teeth of the worm gear 18. The worm 19 is provided with end trunnions 20 rotatably mounted between the ears 21 of a suitable bracket member 22, which is suitably supported by one of the frame members 16. One of the worm trunnions 20 is provided with a suitable handle 23 for turning the worm 19 in either direction, for either winding 40 the cable upon, or unwinding the cable from the drum 13.

Depending from the frame like structure 16 and in vertical axial alignment with the sleeve 17, is a suitable member 24. The member 24 45 projects downwardly a suitable distance from the frame structure 16, is bent forwardly at a right angle thereto, as at 25, a suitable distance to provide a support for one end of a plank 26 for workmen to stand and walk upon while working 50 on the side wall of the building.

The upper end of the vertically disposed member 24 is bent at a right angle thereto to form a support 27 for one end of a plank 28 adapted to serve as means or a bench to support material 55

to be used by the workmen, and without causing the workmen to bend over or reach down to pick up the material. From the drawing, it will be apparent that the work receiving plank 28 is disposed above the run plank 26 and that the planks are arranged on opposite sides of the suspended cable 9, which supports the scaffold support in suspension in such a manner as to obtain an even distribution of weight, thus avoiding undue 10 swinging movement of the scaffold support while workmen are working on the run board 26.

Projecting upwardly from the forward end of the plank supporting member 25, is an upright member, or post 29, the upper end of which is provided with a suitable socket member 30 to receive and support one end of a suitable guide rail 31.

The reversed Z-shaped structure including sections 24, 25, 27, and 29 are braced by means 20 of a suitable brace member 32, the rear end of which can be curved, as at 33 to engage the wall of the building for bracing the scaffold when in use and upon which it slides when raising and lowering the scaffold.

25 It is, of course, understood that in setting up the scaffolding that two standards, or supports 5 are employed and that they are spaced a suitable distance apart adjacent the wall of the building, and that a cable is suspended from each 30 support to hold the plank supporting structure in suspension therefrom so that both ends of the planks will be supported to be raised and lowered by the hoisting mechanism, as desired.

In order to prevent the run planks 26 from 35 shifting longitudinally upon their supporting members 25, I employ a metal member 34, suitably and detachably secured to the plank and having recessed ends to receive the members 24 and 29. This metal member is secured to the 40 plank 26 after the plank has been positioned and it is removed before the plank is removed from the plank supporting structure.

The many advantages of the herein described 45 invention will readily suggest themselves to those skilled in the art to which it appertains.

From the foregoing description, it is evident 50 that a simple device for this purpose has been disclosed, but it is to be understood that I do not desire to restrict, or limit myself to the very 55 details of the construction shown and described, which is merely illustrative, it being obvious that changes, not involving the exercise of invention, may be made without conflicting or departing from the spirit of the invention within the scope 55 of the appended claims.

What I claim is:

1. In a scaffolding, a support, a flexibly resilient metal member secured to and projecting beyond the upper end of the support and adapted to be supported between a building cornice and a guttering, a cable suspended from the upper end of the support, a platform support suspended from the ends of a shaft supporting a drum upon which the lower end portion of the cable is wound, a sleeve carried by the platform support above the drum to serve as a guide for the cable, and means including a worm gear and a worm for imparting rotary motion to said drum for raising and lowering the platform support.
2. In a scaffolding, a support, a flexibly resilient metal member secured to and projecting beyond the upper end of the support and adapted to be supported between a building cornice and a guttering, a cable suspended from the upper end 75 of the support, a platform support suspended

from the ends of a shaft supporting a drum upon which the lower end portion of the cable is wound, a sleeve carried by the platform support above the drum to serve as a guide for the cable, means including a worm gear and a worm for 5 imparting rotary motion to said drum for raising and lowering the platform support, and means carried by the platform support for supporting a guide rail.

3. In a scaffolding, a support, a flexibly resilient metal member secured to and projecting beyond the upper end of the support and adapted to be supported between a building cornice and a guttering, a cable suspended from the upper end of the support, a platform support suspended from the ends of a shaft supporting a drum upon which the lower end portion of the cable is wound, a sleeve carried by the platform support above the drum to serve as a guide for the cable, means including a worm gear and a worm for 10 imparting rotary motion to said drum for raising and lowering the platform support, and said platform support including members on opposite sides 15 thereof for supporting two planks, one above the other, and on opposite sides of the suspension 20 cable.

4. In a scaffold construction having, in combination, a standard, a flat flexibly resilient member 30 secured to and projecting beyond the upper end thereof to be supported between the guttering and cornice of a building so that the standard can assume a leaning position, a cable secured to and adjacent the upper end of and depending vertically therefrom, a frame like structure, a 35 sleeve secured to the upper end of said structure, said cable adapted to pass through and be guided by said sleeve, means carried by the frame like structure and associated with the cable for raising and lowering said frame like structure, said 40 frame like structure adapted to support a run board and a board for materials used by workmen, said boards being disposed one above the other and on opposite sides of the suspension 45 cable.

5. In combination with a single depending cable supported at its upper end, a supporting structure comprising a frame like member, a cable guide sleeve carried at the upper end of the member through which the cable passes, a cable drum upon which the cable is wound and unwound, a shaft journaled in the frame below said sleeve and by which the drum is carried, said frame member being pivotally supported by the ends of said shaft, a dual platform supporting structure depending from said pivotally supported frame and 50 adapted to support planks on either side of the suspension cable, one above the other, the lowermost plank serving as means for workmen to walk on and disposed to the outside of the cable, and the uppermost plank serving to support material 55 to be used by the workmen to obviate the necessity of their bending down, or turning around to pick up the material, and said last mentioned plank being disposed to the inner side of the cable and 60 closest to the wall of a building, guide rail supporting means carried by the dual platform supporting structure, and means for diagonally bracing 65 said structure.

6. In combination, a vertically disposed frame 70 like structure terminating at its lower end in a rearwardly bent section to support a walking plank and said section being bent upwardly to serve as a guide rail support, a sleeve secured to the upper end of the vertically disposed frame like 75

structure and serving as a guide for a single cable suspended from a support, a drum rotatably supported by the frame like structure below the sleeve and upon which drum the cable is adapted to be wound and unwound for raising and lowering the frame like structure, a member secured to and

projecting forwardly from the frame like structure immediately below the cable drum to support a work supporting plank immediately next to a building wall, and bracing means for the frame like structure.

5

JOHN P. BIEBEL.
